The ornamental design for a “splitting wedge system for log splitter,” as shown and described.

DESCRIPTION

FIG. 1 is a perspective view of the splitting wedge system being attached to a log splitter beam of a log splitter.

FIG. 2 is a right side view of the perspective view of FIG. 1.

FIG. 3 is a perspective view of the splitting wedge system of FIG. 1.

FIG. 4 is a top view of the splitting wedge system of FIG. 1.

FIG. 5 is a right side view of the splitting wedge system of FIG. 1, the left side being a mirror image thereof.

FIG. 6 is a front view of the splitting wedge system of FIG. 1.

FIG. 7 is a rear view of the splitting wedge system of FIG. 1; and,

FIG. 8 is a bottom view of the splitting wedge system of FIG. 1.

A left side view of the splitting wedge system of FIG. 3 a has been omitted because it is a mirror image of the right side view of FIG. 3c.

All broken lines are for illustrative purposes only and form no part of the claimed design.
